UNITED STATES PATENT OFFICE.

SAMUEL D. LOVE, OF NEW YORK, N. Y.

WATER-SUPPLY SYSTEM.

SPECIFICATION forming part of Letters Patent No. 514,090, dated February 6, 1894.

Application filed October 9, 1893. Serial No. 487,568. (No model.)

To all whom it may concern:

Be it known that I, SAMUEL D. LOVE, a resident of the city, county, and State of New York, have invented new and useful Improvements in Water-Supply Systems, of which the following is a specification.

My invention relates to water supply systems and has for its object to maintain a constant pressure throughout the service pipes of 10 large buildings or other elevated structures without the use of tanks or other reservoirs on top of such structures.

To this end my invention consists in the mechanism described and illustrated in the 15 accompanying drawings, forming part hereof and more particularly pointed out in the claims.

In the drawings—Figure 1 is a diagrammatic view of my improved system; and Fig. 20 2 and 3 are sectional elevations of details to be hereinafter described.

a is a supply pipe which brings water from the main in the street to the pump b. The 25 pump is a steam pump of any ordinary construction supplied with steam through the pipe e and regulated by the throttle i.

c is a pipe extending from the pump throughout the structure to be supplied with water, and represents the service pipe or suitable 30 stand pipe.

In the steam pipe e I place a suitable valve h to cut off the steam to stop the working of the pump, as it will be hereinafter described.

Communicating with the service pipe c and 35 preferably mounted thereon I place a controlling device g for the valve h. In Fig. 2 this controlling device g is shown in section and consists of a cylinder g⁵ communicating with the interior of the service pipe, and adapted 40 to receive water therefrom. In this cylinder works a piston g⁶ having a stem g⁷ surrounded by a spring g⁸, which, bearing against the piston and the head of the cylinder, serves to keep the piston pressed forward in the cylinder. Surrounding the cylinder g⁵ is a casing g' insulated from the pipe c, and carrying thereon a circuit terminal g² and a contact screw g³. The valve h is represented in section in Fig. 3, and consists of an ordinary gate valve 45 h' carried by a stem h² and held up out of the way h³ by the spring h⁴. Supported in prox-

imity to the valve stem are magnets h⁵ whose armature h⁶ is attached to the valve stem h². From the circuit terminal g² of the controlling device g a wire 1 extends to the battery f. Connected to the cylinder g⁵ is the wire 2 which passes through the casing g' and is insulated therefrom, and extends to the magnets h⁵. The wire 3 connects the magnets h⁵ with the battery f.

The operation of the system is as follows: The valve i being supposed to be open and the pump in operation, the water will go through the pipe a to the pump and be supplied to the building through the service pipe 65 c. As long as the water is allowed to flow freely, the piston g⁶ will be held firmly in the position shown in Fig. 2 by the spring g⁸. As soon as the water is shut off in the pipe c, we will suppose at the point c', the flow through 70 the pipe c will stop and the piston of the pump in moving will now cause a higher pressure of the water in the pipe which will have the effect of forcing the piston g⁶ back in its cylinder against the tension of the spring 75 g⁸. As soon as the piston g⁶ is moved far enough to allow its end g⁴ to make contact with the contact screw g³, the circuit will be completed through the battery wire 1, binding-post g², casing g', contact screw g³, stem 80 of the piston g⁶, cylinder g⁵, wire 2, magnets h⁵, by wire 3, back to the battery. The magnets h⁵ will now attract their armature h⁶ and close the valve against the tension of the spring h⁴. This will have the effect of shutting off steam from the pump which will then stop working. As soon as the flow of water is again established in the pipe c by opening the cock c' or otherwise, the pressure on the piston g⁶ will be relieved and the spring g⁸ 90 will force the piston forward, and will break the circuit at g³, g⁴. As soon as the circuit is broken, the magnets g⁵ will no longer attract their armature and the spring h⁴ will immediately lift the valve and allow steam to be 95 admitted to the pump, which will then be operated to keep up the pressure to supply the building as before.

It may happen that for some cause the pressure in the pipe c is not maintained high 100 enough, when the water has been shut off in the building as described, to maintain the pis-

ton g^6 against the pressure of the spring g^8 , but this will be of no consequence since, as soon as the piston moves far enough forward to break the circuit, the pump will immediately get up the pressure and force out the piston, completing the circuit again, which will stop the pump as before. This will happen as often as the parts g^4 and g^8 become separated while the water in the service pipe is not flowing and the pressure will at all times be maintained. It will be seen that by providing an automatic means for controlling the pump by the pressure of the water in the service pipe, I succeed in entirely dispensing with tanks in elevated positions to feed the service pipes, thus obviating all the objectionable features of such tanks.

I do not limit myself to the construction described and shown herein nor to any specific devices for accomplishing the same purposes as it is obvious that the devices may be greatly varied without departing from the spirit of my invention, but

What I claim, and desire to secure by Letters Patent, is—

1. In a system of water distribution, the combination of a steam pump feeding a service pipe, an electro-magnetic valve for controlling the supply of steam to the pump, a pressure operated circuit closer controlling the circuit of the electro-magnetic valve, communicating with the service pipe, whereby the electro-magnetic valve may be controlled

by the water pressure in the service pipe, substantially as described. 35
2. In a system of water distribution, the combination of a steam pump feeding a service pipe, an electro-magnetic valve for controlling the supply of steam to the pump, a pressure operated circuit closer in circuit therewith, communicating with the service pipe, whereby the electro-magnetic valve may be controlled by the water pressure in the service pipe, substantially as described.

3. In a system of water distribution the combination of a steam pump feeding a service pipe, an electro-magnetic valve for controlling the supply of steam to the pump, a casing, in electrical circuit with the steam valve, mounted on the service pipe but insulated therefrom, a cylinder covered by said casing and in electrical circuit with the steam valve, communicating with the interior of the service pipe and adapted to receive water therefrom, a spring pressed piston in said cylinder, a piston rod extending therefrom adapted to make contact with the casing, all arranged so that a predetermined movement of the piston will energize the electro-magnet of the steam valve, substantially as shown and described. 50
